UNITED STATES PATENT OFFICE.

GEORGE GODDU, OF WINCHESTER, AND FRED L. MACKENZIE, OF BEVERLY, MASSACHUSETTS, ASSIGNEES TO UNITED SHOE MACHINERY CORPORATION, OF PATERSON, NEW JERSEY, A CORPORATION OF NEW JERSEY.

MACHINE FOR INSERTING FASTENINGS.

1,399,765.

Specification of Letters Patent. Patented Dec. 13, 1921.

Application filed January 10, 1919. Serial No. 270,502.

To all whom it may concern:

Be it known that we, GEORGE GODDU and FRED L. MACKENZIE, citizens of the United States, residing at Winchester, in the county of Middlesex, and Beverly, in the county of Essex, respectively, and State of Massachusetts, have invented certain Improvements in Machines for Inserting Fastenings, of which the following description, in connection with 10 the accompanying drawings, is a specification, like reference characters on the drawings indicating like parts in the several figures.

This invention relates to machines for inserting fastenings and has for its object to provide improved mechanism for varying the operation of such a machine on the work as is frequently rendered necessary or desirable by dissimilarity in character of the 20 separate pieces of work operated upon or of different parts of the same piece of work.

The invention will be hereinafter described, by way of example, as applied to a machine for inserting loose nails of the type disclosed in the Patent to Goddu, 1,030,775, June 25, 1912. In order to adapt machines of such type for operation on pieces of shoe stock of different thicknesses or on stock which varies in thickness at the points where 30 nails are inserted, the raceways of the machines are formed with a plurality of slots adapted to contain nails of different lengths, and means are provided for causing nails of relatively great length to be supplied to the fastening inserting mechanism for insertion into relatively thick stock and for causing nails of less length to be supplied to the fastening inserting mechanism when relatively thin stock is being operated upon. The conditions which require change in the length of the nails being inserted also frequently make necessary a change in the position of the gage by which the work is guided in the operation of such machines. For example, when 40

45 nailing around the edge of a shoe, the thickness of the stock through which the nails are driven is frequently greater at the forepart than in the shank, by reason, for instance, of the interposition of a slip sole between the outsole and insole at the forepart. Consequently, it is advisable to insert a longer nail in the forepart than in the shank. The edge of the outsole also frequently projects farther beyond the edge of the insole at the forepart

than in the shank, for which reason the gage 55 should preferably be moved away from the plane of operation of the fastening inserting mechanism upon the initiation of the insertion of long nails to cause the row of nails to be spaced farther from the edge of the shoe 60 at the forepart than in the shank.

It has heretofore been proposed to provide common controlling means for the fastening inserting mechanism and the gage operable to shift the gage from one guiding position 65 to another substantially simultaneously with the effectuation of a change in the length of the nails inserted by the fastening inserting mechanism to facilitate the control of the machine by the operator by reducing the 70 number of operations which it is necessary for him to perform in controlling the machine and to insure that the shifting of the edge gage which might be neglected by the operator will be effected at the proper time. 75 Another object of the invention is to improve the character of such controlling means, the illustrated embodiment of the invention being characterized by the provision of power-operated means for automatically controlling 80 the fastening inserting mechanism and effecting movement of the gage.

The construction and manner of operation of the fastening inserting instrumentalities and work support of machines of the type 85 disclosed in the above-mentioned patent is such that forward movement of the work and consequently of the edge gage is permitted during a small part only of the cycle of operations of the machine, namely, while 90 the awl is passing through the latter part of its feeding movement and is being withdrawn from the work. Accordingly, the operation of the edge gage moving means is so timed as to urge the gage forwardly 95 during such part only of the cycle of operations. The arrangement of the awl and edge gage relatively to each other and to the work is such that an extensive movement of the gage in a forward direction imposes a 100 strain on the awl tending to bend it. In the embodiment of the invention now preferred by us, the imposition of such strains on the awl is obviated by the provision of power-operated means for moving the gage step by 105 step from one guiding position to another in each of which it will determine the spacing of a row of fastenings from the edge of

the work. Since the gage is moved one step only intermediate between the insertion of consecutively inserted fastenings, a number of fastenings are inserted between the rows of fastenings. Preferably, and as exemplified in the construction illustrated in Figs. 1 to 7 inclusive of the drawings, normally stationary operator controlled means is associated with the power-operated means for 10 operatively connecting and disconnecting the power-operated means with and from the gage.

Although the invention will hereinafter be described as embodied in a machine for inserting loose nails, it is recognized that the use of the invention is not restricted thereto but that the invention as a whole and certain features thereof may have other applications including incorporation in other types of fastening inserting machines. Moreover, the illustrated mechanism may be materially modified without departing from the scope of the invention as defined in the claims.

Other objects and features of the invention 25 will appear as the description proceeds and will be pointed out in the appended claims.

In the drawings,

Fig. 1 is a view in side elevation of the head of a fastening inserting machine embodying the invention;

Fig. 2 is a view in detail of the gage member and slide;

Fig. 3 is a detail of the cam member which directly controls the movement of the gage 35 by its operating means;

Fig. 5 is a view in plan of a part of the 40 connections by which the raceway is shifted;

Fig. 6 is a plan view partly in cross-section of the edge gage;

Fig. 7 is a view in side elevation of the 45 edge gage and its operating means;

Fig. 8 is a view in elevation of a modified form of the invention;

Fig. 9 shows the gage and its operating means in such form; and

Fig. 10 portrays a shoe exemplifying the 50 work which the invention is designed to accomplish.

The machine in which the invention is herein illustrated as embodied comprises a column 2 which supports the head 4 upon the front end of which are mounted the fastening inserting instrumentalities comprising the awl 6. A gage 8 is carried on the under side of the head adjacent to the point of 55 insertion of the fastenings and acts to determine the spacing of the fastenings from the edge of the work.

Means are provided for controlling the inserting mechanism so as to cause it to insert 60 selectively nails of different lengths. In the

illustrated construction, such means is generally of the type disclosed in the patent to Mackenzie 1,262,820, dated April 16, 1918, and for convenience in comparing the machine herein disclosed with that of said patent, similar reference numerals will be used to designate similar parts. The slide 280, upon which is mounted the actuator for shifting the raceway in the form of a double pawl 502, is reciprocated to bring said pawl 75 into and out of engagement with one or the other of two shoulders 302 and 306 upon a horizontal slide 304 by connections with a bell crank lever 182, comprising a rack 294 mounted upon said slide 280, and engaged by a segment rack 296 upon an arm 298 of the bell crank lever 182. The other arm of the lever 182 carries a cam roll which enters the cam groove 184 in the cam 48 upon the shaft 20 of the machine. The connections between the slide 304 and the double raceway 264 which has two slots designed to receive relatively long and short nails respectively comprise, as shown in the patent to Goddu hereinafter mentioned, oppositely 80 threaded rods 308 and 310 connected by an adjusting nut 312, the rod 308 being pivotally connected to the lug 314 upon the side of the double raceway. The rod 310 receives in an opening at one end an eccentric 85 carried on the lower end of a rock shaft mounted in a bearing in the bracket 272, said rock shaft having formed upon its upper end a pinion 320 with which meshes a segment rack 322 formed on the end of the rock arm 324 which is clamped upon the upper end of the rock shaft 326 also mounted in a bearing in the bracket 272 and carrying at its lower end a segment gear 328 which meshes with rack teeth 330 on the slide 304. The rack teeth 330 are disposed at an inclination to the slide bar 304 and the bearings for the rock shaft 326 and 318 are correspondingly inclined thus serving to prevent binding when the inclined raceway is moved. The shifting movement of the slide 304 is sufficient to turn the eccentric upon the shaft 318 around from one dead center to the other with respect to the rod 310 so that the raceway is positively shifted and positively held in either of its positions.

The pawl 502 is under the control of a pawl tipper 606 comprising arms 608 and 610 which carry respectively the dogs 536 and 538. The pawl tipper 606 is formed with a hub mounted to turn freely on the shaft 614. The slide 280 is operated by power from the cam 48, being moved downwardly far enough for the pawl 502 to be engaged and turned about its axis by the dog 536 or 538 whenever the pawl tipper 606 has been set to effect shifting of the raceway. If the tipper is turned to the right to the position indicated in Fig. 4, the pawl 502 will be oscillated on its fulcrum 602 so as 130

to cause its right hand end (Fig. 4) to engage the shoulder 302 of the slide 304 and thus shift the raceway in one direction. On the other hand, movement of the pawl tipper 5 606 to the left effects engagement of the left hand end of the pawl 502 with the shoulder 306 whereby the raceway is moved in the opposite direction. The pawl tipper is normally in short nail position, *i. e.*, in position 10 to cause the raceway to deliver short nails to the inserting mechanism, being yieldingly maintained in such position by a spring 636 (Fig. 4) which is connected at one end to a screw or stud 638 upon the bracket 272 which 15 carries the raceway shifting mechanism and at its other end is bent down so that it enters a socket 640 in the upper face of a bell crank lever 642 fulcrumed upon a stud 644 and having at its forward end a short rack 646 20 which engages teeth 648 in the periphery of the circular body portion of the tipper 606. Between the stud 644 and the pawl tipper 606, the arm of the bell crank 642 is provided with an opening which receives 25 a stud 650 serving as a stop for the vertical movements of the arm, the opening being larger in diameter than the stud 650 whereby movement of the arm sufficient to 30 rock the pawl tipper between its two pawl tipping positions can take place.

Preferably, for the purposes of this invention, the operation of the raceway shifting means is under the control of the operator. To this end, the bell crank lever 35 642 is formed with a second arm 676 having a stop face 678 over which hooks a dog 680 guided upon a stud or screw 688 received in a slot 686 of the dog for limiting its longitudinal movement and pivotally connected to an arm of another bell crank 682 40 fulcrumed at 684 upon a rearward extension of the bracket 272. A second arm 690 of the bell crank 682 is formed with a vertical bore through which slides a rod 692 upon which 45 is clamped a collar 694 between which and the arm 690 of the bell crank lever is interposed a spring 696 through which force is transmitted from the rod 692 to the bell crank 682. The rod 692 is normally urged 50 downwardly by a spring 698 acting against a part 700 fixed to the machine frame and a clamp collar 702 on the rod. Upward movement of the rod 692 is effected by a treadle 704 and causes the pawl tipper 606 55 to be moved in opposition to the resistance of the spring 636 in a manner to initiate the movement of the raceway to a position to deliver a long nail.

The edge gage and its adjusting means 60 will now be described. As shown, the gage is provided with a work engaging member 706 formed to present a bearing surface 708 arranged to maintain guiding engagement with the work in any of its positions of 65 adjustment. The member 706 is secured to

the under side of a lateral extension 710 on the front end of a carrier or slide 712 guided in a channel formed in a block 714 secured to the head 4 of the machine by suitable means such as bolts or the like. The gage 70 is designed to be moved forwardly by the power of the machine and, to this end, the lateral extension 710 is preferably provided with means adapted to be engaged by the power operated means. In the illustrated 75 construction, the lateral extension 710 is formed on its upper surface with teeth or corrugations 716 constructed for operation by a pawl 718 fulcrumed in an extension 720 of the lever 722 by which the awl is 80 forced downward to penetrate the work. The pawl 718 is engaged forwardly of its fulcrum 724 by a plunger 726 seated in a recess in the extension 720 and pressed against the pawl 718 by a spring 728 to maintain 85 the active end of the pawl normally down in a position to engage the teeth 716 of the slide 712. The movement of the pawl under the impulse of the spring 728 is limited by a stop 730 disposed to engage its rear end. 90 The range of movement of the pawl 718 by the lever 722 is such as to move the gage through a small distance only at each operation, a number of operations of the pawl being required to accomplish the movement 95 of the gage from its rearward to its forward position of adjustment. Inasmuch as the pawl is operated but once in each cycle of operations of the machine, it follows that in changing the insertion of the nails from 100 one row to another, a number of nails will be inserted intermediate between adjacent ends of the rows, such nails being one less in number than the steps in the forward movement of the gage. The mechanism constituting the present exemplification of the invention is designed to effect forward movement of the gage in three steps so that two 105 nails are inserted between the rows.

In order to preserve each of the accretions of movement of the gage in a forward direction and to retain the gage in its forward position of adjustment, the pawl 732 is pivoted on a stud 734 on the block 714 and is spring pressed downwardly into engagement with the teeth 736 on a second lateral extension 738 formed on the slide 712. The slide 712 is returned to its rearward position of adjustment by a spring 740 one end of which is received in a thimble 742 which is thereby pressed against a pin 744 depending from the slide 712 into a slot 746 in the block 714. A set screw 748 is projected into the end of the slot opposite the thimble 742 and constitutes an adjustable stop for limiting the movement of the gage by the spring 740.

The operating means for the edge gage is controlled by the operator by means comprising a double cam member 750 slidably 130

mounted on the block 714 and having a forward cam section 752 operable to elevate the active end of the pawl 718 from the teeth 716 and to retain the pawl in such 5 position to preclude movement of the slide thereby and a second cam section 754 for raising the pawl 732 from engagement with the teeth 736 on the lateral extension 738 to permit the gage to be moved backwardly 10 by the spring 740. The member 750 is normally urged rearwardly by a spring 755 received in a thimble 756 engaging the depending end 757 of said member and is provided with a recess 758 which receives a 15 stud 759 on an arm 760 mounted on a shaft 762 journaled in the block 714 and having at its other end an arm 763 connected by a link 764 to the arm 766 formed with the bell crank lever 682 so that upon actuation 20 of the rod 692 by the treadle 704, the operation of the raceway shifting mechanism and the gage moving means may be simultaneously initiated.

The manner of operation of the invention 25 will be described with particular reference to Fig. 10 which shows a shoe comprising an upper A, outsole B, and slip sole C. The shoe is presented to the machine in the usual manner, *i. e.*, with the toe at the right of the 30 point of insertion of the nails. The gage being in its forward position of adjustment and the raceway being in a position to deliver short nails, a row of such nails indicated by the bracket D is inserted in the shank of the 35 shoe close to its edge. When the fore part is reached, however, the operator depresses the treadle 704 and thereby moves the pawl shifter so that upon the next operation of the slide 280, the raceway 264 is shifted to a position to deliver long nails as required by 40 the greater thickness of the material in the forepart. The depression of the treadle also through its connections with the arm 760 moves the cam member 750 forwardly thus 45 elevating the pawls 718 and 732 from the gage slide 712, whereupon the gage is moved to its rearward position of adjustment by the spring 740, which is also its retracted gaging position. Upon continued operation of the 50 machine, therefore, a row of long nails is inserted about the forepart at a distance more remote from the edge of the shoe than in the shank which as hereinbefore pointed out is desirable because of the greater projection 55 of the sole in the forepart. When the shank of the shoe is reached on the other side, the operator removes his foot from the treadle thus permitting the pawl shifter 606 to be 60 moved to short nail position by the spring 636 and the cam member 750 to be thrust back by the spring 755 to effect engagement of the pawls 718 and 732 with the gage. The lever 722 is operated to begin the withdrawal of the awl from the work before the 65 feeding movement of the awl is completed.

Consequently, inasmuch as the pawl 718 is actuated in a direction to move the gage forwardly when the lever 722 raises the awl, forward movement of the gage will be effected during the latter part of the feeding movement of the awl and while the awl is in the work. The machine is thus caused to insert short nails at the proper decreased distance from the edge of the shoe. The nails, which as above mentioned are inserted in the shoe 75 intermediate between the rows, are designated in Fig. 10 by the reference characters E and F respectively, and the row of short nails in the shank is marked out by the bracket H. From the foregoing, it will be 80 understood that the operation of the machine on a piece of work is completed with the gage in forward position, that is, with the gage in advanced gaging position, and that the gage will be in such position when a fresh 85 piece of work is presented to the machine.

In the employment of fastening inserting machines on many kinds of work, for example, in the manufacture of shoes of certain styles, it is necessary to move or adjust the 90 gage during the operation of the machine on a single piece of work. The adjustment of the edge gage is effected without checking the operation of the machine, and has heretofore, so far as applicant is aware, been 95 manually performed. Inasmuch as the machine operates very rapidly and the edge gage is capable of adjustment in the direction of the work during the small part only of the cycle of operations of the machine in 100 which the awl is passing through the latter part of its feeding movement and is being withdrawn from the work, the work and, consequently, the gage being withheld from movement at other times by reason of being 105 clamped between the work support and foot plate of the machine or by reason of the projection of the awl into the path of movement of the gage, the operator must act very quickly to effect complete adjustment of the 110 gage at the desired point of the work. Consequently, in prior constructions, it results frequently that the operator effects only an incomplete adjustment of the gage in the short space of time permitted for the operation, thus causing uneven work. The provision, in the illustrative machine, of power operated means for effecting the movements of the gage, it being understood that the gage is moved rearwardly by power stored in the 115 spring on its forward movement, insures prompt movement to the full limit of its adjustment in either direction.

The embodiment of the invention illustrated in Figs. 8 and 9 is applied to a machine 125 in which the raceway is automatically shifted by mechanism of the type shown in the patent to Goddu above mentioned. Many of the elements of such mechanism are identical with parts of the raceway shifting means 130

hereinbefore set forth, and since it is believed that a further reference to such parts is unnecessary to a complete disclosure of the invention, the mechanism will be described 5 only in the respects in which it differs from such construction. In the operation of machines of the type disclosed in the Goddu patent, the work is mounted on a horn 780 by which it is held against the foot plate of 10 the machine. The horn and foot plate serve to caliper the work and inasmuch as the foot plate is fixed in its position, the horn will be elevated to an extent depending upon the thickness of the work at the point engaged 15 by it. The double pawl 502 is automatically shifted by a pawl shifter 782 controlled by connections with the horn 780 so that the raceway 264 is shifted to deliver a long nail or a short nail according to the thickness 20 of the work indicated by the horn. The pawl shifter 782 is mounted on a shaft 784 having at one end a pinion 786 meshing with teeth on a segment arm 788 extending from a shaft 790 upon which is mounted a lever 792 connected by a link 794 with a lever 796 fulcrumed on the machine frame and connected to the horn 780 at 798.

Slidably mounted on a bracket 800 carried by the machine frame is a gage member 802 30 having a spring 804 connected thereto and tending to move the gage rearwardly. A set screw 806 disposed to engage a pin 808 depending from the gage slide adjustably limits the movement of the gage in such 35 direction.

To the end that the gage may be automatically moved from one gaging position to another, the slide bar 304 is extended beyond the rack 330 as indicated at 809 and 40 has secured in its end a stud 810 grooved to receive the hooked end of a link 812 joined to the upper end of a lever 814 fulcrumed at 816 to an upwardly extending portion 818 of the bracket 800. The lever 814 is provided at its lower end with teeth meshing 45 with a pinion 820 on a shaft 822 journaled in the bracket 800 and formed with an eccentric portion 824 engaging a lug 826 on the gage slide and operable upon angular 50 movement of the shaft 822 to move the gage forwardly in opposition to the spring 804. A spring 828 connected at one end to a pin 830 on the link 812 and at its other end to the pin 832 retains the link 812 in engagement 55 with the stud 810 but permits it to be readily detached from the stud when desired. The arrangement of the above-described parts is such that when the bar 304 is moved in a direction to shift the raceway 60 to short nail position, the extension 809 of the bar through its connections with the gage moves it forwardly against the resistance of the spring 804. When, on the other hand, the bar 304 is moved in the opposite 65 direction so as to effect movement of the

raceway to a position to deliver long nails, the shaft 822 is rotated to withdraw its eccentric portion whereupon the gage is moved back by the spring.

Having described our invention, what we 70 claim as new and desire to secure by Letters Patent of the United States is:

1. In a machine of the class described, fastening inserting mechanism comprising a raceway having a plurality of slots adapted 75 to support and guide fastenings of different character, means for shifting the raceway to change the character of fastening inserted by said mechanism, controlling means for the shifting means, a gage for positioning the work relatively to the fastening inserting mechanism by engagement with the edge of the work, and power-operated means rendered operative by movement of the controlling means to effect movement of the 80 gage from one gaging position to another concurrently with the shifting of the raceway.

2. In a machine of the class described, fastening inserting mechanism constructed 90 and arranged to insert fastenings of varying character, means for feeding the work relatively to the fastening inserting mechanism to cause the insertion of a row of fastenings in the work, means for changing the character of fastening inserted by the fastening inserting mechanism, controlling means for said changing means, a gage formed to present a bearing surface for engagement with the edge of the work to determine the spacing 95 of the row of fastenings from the edge of the work, means connected with the work feeding for moving the gage so as to change the spacing of the row of fastenings from the edge of the work, and means connected 100 with said controlling means for rendering the edge gage moving means operative or inoperative on the gage.

3. In a machine of the class described, fastening inserting mechanism constructed 110 and arranged to insert fastenings of varying character, means for changing the character of fastening inserted thereby, controlling means therefor, an awl for feeding the work relatively to the fastening inserting mechanism, means for operating the awl in directions to penetrate the work and to feed the work, a gage formed to present a bearing surface for engagement with the edge of the work to determine the spacing of a row 115 of fastenings from the edge of the work, means connected with the awl operating means for moving the edge gage to change the spacing of the row of fastenings from the edge of the work, and means connected 120 with the controlling means for rendering the edge gage moving means operative or inoperative on the gage.

4. In a machine of the class described, fastening inserting mechanism, a gage 125

- formed to present a bearing surface for engagement with the edge of the work to position the work relatively to the fastening inserting mechanism, means for determining a plurality of positions of adjustment of the gage in each of which it will determine the spacing of a row of fastenings from the edge of the work as the work is moved past the fastening inserting mechanism, power-operated means for moving the gage step by step from one of such positions of adjustment to another, means for rendering the power-operated means inoperative on the gage, and means for effecting reverse movement of the gage when the power-operated means is rendered inoperative. 5. In a machine of the class described, fastening inserting mechanism, means for feeding the work relatively to the fastening inserting mechanism to cause the insertion of a row of fastenings in the work, a gage formed to present a bearing surface for engagement with the edge of the work to position the work relatively to the fastening inserting mechanism, means for determining a plurality of positions of adjustment of the gage in each of which it will determine the spacing of a row of fastenings from the edge of the work, power-operated means for moving the gage forward step by step from a position of adjustment more remote to one less remote from the plane of operation of the fastening inserting mechanism during a plurality of operations of the fastening inserting mechanism so as gradually to change the disposition of the fastenings from location in one row to location in the other row, operator controlled means arranged to be interposed between the power-operated means and the gage to render the power-operated means inoperative on the gage, and means for effecting rearward movement of the gage when the power-operated means is rendered inoperative. 6. In a machine of the class described, fastening inserting mechanism, means for feeding the work relatively to the fastening inserting mechanism to cause the insertion of a row of fastenings in the work, a gage formed to present a bearing surface for engagement with the edge of the work to determine the spacing of the row of fastenings from the edge of the work, means for positively moving the gage step by step in one direction, means separate from the moving means for retaining the gage in the position to which it is thus moved, means for rendering the retaining means inoperative to permit movement of the gage, and means for moving the gage in the opposite direction when the retaining means is rendered inoperative. 7. In a machine for inserting fastenings, a gage, power-operated means constructed and arranged to move the gage forward through a plurality of steps from one operative position to another and maintain it in such position during a plurality of fastening inserting operations, means tending normally to move the gage in the opposite direction, and means separate from the power-operated means for retaining the gage against movement in such last-named direction. 8. In a machine of the class described, a gage movable in a direct line into and out of a plurality of operative positions, power-operated means for moving the gage, and normally stationary operator controlled means for operatively connecting and disconnecting the power-operated means with and from said gage. 9. In a machine of the class described, a gage, power-operated means for moving the gage comprising a member movable into and out of engagement with the gage, and normally stationary manually controlled means for engaging said movable member with and disengaging it from the gage. 10. In a machine of the class described, a gage, means for moving said gage comprising a lever and a pawl movably mounted on said lever for engagement with or disengagement from said gage, and normally stationary operator controlled means for engaging said pawl with or disengaging it from said gage. 11. In a machine of the class described, a gage mounted for sliding movement, a member connected with the gage for bodily movement therewith, and power-operated means for moving the gage comprising a manually controlled element movable into and out of engagement with said member. 12. In a machine of the class described, a gage movable between advanced and retracted gaging positions, power-operated means for moving the gage toward advanced gaging position, means for retaining the gage in the position to which it is moved by said power-operated means, and means for simultaneously disengaging the power-operated means and the retaining means from the gage to permit the latter to move to retracted gaging position. 13. In a machine of the class described, a gage movable between advanced and retracted gaging positions, means for moving the gage toward advanced gaging position comprising a power-operated lever having a member movably mounted thereon for engagement with or disengagement from the gage, means for retaining the gage in the position to which it may be moved by said power-operated lever, means having parts co-acting with said lever and said retaining means for simultaneously disconnecting said lever and said retaining means from said

gage, and means for moving the gage to retracted gaging position when released from control by said retaining means.

14. In a machine of the class described, a gage, power-operated means for moving the gage, a member independent of the power-operated means and operable to retain the gage in the position to which it is moved by said power-operated means, and means for simultaneously rendering said moving means and said member inoperative on said gage.

15. In a machine of the class described, a gage movable between advanced and retracted gaging positions, a member connected to said gage and having teeth or the like formed thereon, means operatively associated with said teeth for moving the gage member toward advanced gaging position, a second member connected to the gage member and formed with teeth or the like, a pawl normally engaging said last mentioned teeth to retain the gage member in any position to which it may be moved by said moving means, and means having parts co-acting with said moving means and with said pawl to disconnect the moving means and the pawl simultaneously from said gage to per-

mit the latter to move to retracted gaging position.

16. In a machine of the class described, a work support arranged to support a shoe in inverted position, mechanism for inserting a row of metallic fastenings in the bottom of the shoe comprising means for feeding the work, gaging means for guiding the work as it is fed, said gaging means comprising a single gaging member having its bearing surface constantly in position to guide the work by engagement with the edge of the work and operating to determine the spacing of the row of fastenings from the edge of the work, an actuator carried by and movable with a part of said mechanism for moving the gage in a direction toward the plane of operation of the fastening inserting mechanism to decrease the distance by which the row of fastenings is spaced from the edge of the work, and manually controlled means for moving the actuator out of operative relation to the gage.

50 In testimony whereof we have signed our names to this specification.

GEORGE GODDU.

FRED L. MACKENZIE.

Certificate of Correction.

It is hereby certified that in Letters Patent No. 1,399,765, granted December 13, 1921, upon the application of George Goddu, of Winchester, and Fred L. Mackenzie, of Beverly, Massachusetts, for an improvement in "Machines for Inserting Fastenings," an error appears in the printed specification requiring correction as follows: Page 5, line 103, claim 2, after the word "feeding" insert the word *means*; and that the said Letters Patent should be read with this correction therein that the same may conform to the record of the case in the Patent Office.

Signed and sealed this 7th day of March, A. D., 1922.

[SEAL.]

WM. A. KINNAN,

Acting Commissioner of Patents.
